OUTDOOR STOVE STRUCTURE

Stanley C. Hester, Pontiac, Mich.

Application July 10, 1940, Serial No. 344,783

5 Claims. (Cl. 126—8)

This invention relates to an outdoor stove structure.

The invention aims to provide, in a manner as hereinafter set forth, a stove structure of the class referred to for grilling steaks, chops, as well as for cooking and baking different articles of food outdoors on picnics, at camps and amusement parks or at any other desired outdoor place.

The invention further aims to provide, in a manner as hereinafter set forth, an outdoor stove structure including a grille and an oven located above and disposed in rearward relation with respect to the grille.

The invention further aims to provide, in a manner as hereinafter set forth, an outdoor stove structure including a chimney and a stove body built in the chimney, the stove body having a grille, and the chimney and stove body having correlating means to constitute an oven above the grille.

The invention further aims to provide, in a manner as hereinafter set forth, an outdoor stove structure having a grille, and a pair of shiftable cover members over the grille, one functioning as the door for an oven and the other as a support extended forwardly from the grille when the stove is active.

The invention further aims to provide, in a manner as hereinafter set forth, an outdoor stove structure including a grille formed of a pair of hinged oppositely disposed hinged or pivoted sections and a cover for the grille formed of a pair of hinged or pivoted oppositely disposed sections, and a pair of spaced parallel pivots each common to a grille section and a cover section.

The invention further aims to provide, in a manner as hereinafter set forth, an outdoor stove structure which is simple in its construction and arrangement, strong, durable, readily assembled, pleasing in appearance, thoroughly efficient in the use intended thereby, reducing fire hazards to a minimum when the stove is used and comparatively inexpensive to manufacture.

Embodying the aims aforesaid and others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed.

In the drawings—

Figure 1 is a perspective view of an outdoor stove structure in accordance with this invention.

Figure 2 is a fragmentary view in side elevation of the stove structure with the cover sections forming elements thereof extended to constitute supports,

Figure 3 is an elevation of and looking towards the inner face of the outer section of either side member of the stove structure,

Figure 4 is an elevation of and looking towards the inner face of the front member of the stove structure,

Figure 5 is an elevation of and looking towards the inner face of the outer section of the back member of the stove structure,

Figure 6 is a fragmentary view in vertical section of the stove structure with a cover section extended,

Figure 6A is a section on line 6a—6a, Figure 1, Figure 7 is a front elevation of a modified form of outdoor stove structure in accordance with this invention,

Figure 8 is a section on line 8—8, Figure 7, Figure 9 is a section on line 9—9, Figure 8,

Figure 10 is a section on line 10—10, Figure 8, Figure 11 is a detail in elevation illustrating the damper for attachment to the back member, and

Figure 12 is a fragmentary view in vertical section on line 12—12, Figure 3.

With reference to Figures 1 to 6a and 11, an outdoor stove structure, in accordance with the invention includes a front member 12, a pair of oppositely disposed side members 13, 14 of like form and a back member 15. The said members 12, 13, 14, 15 are detachably secured together to form a vertically disposed hollow body 16 open at its top and bottom. The said members 13, 14 are provided at their front and rear with depending integral supporting legs 17 for supporting body 16 in spaced relation with respect to a support such as the ground.

The front member 12 is formed with a pair of spaced superposed door openings 18, 19 normally closed by a pair of superposed doors 20, 21, respectively. The doors are disposed on the outer face of the member 12, are detachably hinged at one side thereof, as at 22 to member 12 and at their other sides are formed with laterally extending handles 23 for seating on the superposed spaced aligned beveled lugs 24 disposed on the outer face of member 12. The latter in proximity to each of its side edges is formed with a pair of spaced superposed aligned openings 25.

The member 12 has its rear or inner face formed with an endless rib 26 having opposed portions 27 flush with its top and bottom edges and oppositely disposed opposed portions 28 of like form spaced inwardly from its side edges. Each portion 28 is formed with a pair of spaced superposed aligned inwardly extending V-parts 29 each partly surrounding in spaced relation an opening 25. The member 12 has its rear or inner face provided with a pair of superposed endless ribs 30, 31, which are flush with the walls of the openings 18, 19, respectively. Reinforcing ribs 32 are also provided on the inner or rear face of member 12 between the ribs 30, 31 and reinforcing ribs 33 and between the ribs 30, 31 and the rib 26. The member 12 at its upper and at its lower end is formed with outwardly directed flat flanges 34, 35, respectively, which are flush with the top and bottom edges of said member. The flange 34 constitutes a combined support and anchor for a purpose to be referred to.

Each of the side members 13, 14 with reference to Figures 3 and 6A includes an outer section 36 in the form of a frame and an inner section 37 in the form of a panel mounted in and detachably connected to the section 36. The latter is formed of an upper part 38, a lower part 39, a front part 40 and a rear part 41. The parts 40, 41 are of like form, are arranged between and merge into the parts 38, 39. The inner edge of the section 36 is indicated at 42. The inner face of section 36 is formed with an endless rib 43 which is spaced from said edge 42 to thereby form such section with an endless rectangular abutment 44 and an endless rectangular shoulder 45 surrounding the abutment 44. The top portion of the abutment 44 has formed integral therewith a pair of spaced aligned offset inverted L-shaped lugs 46 forming grooves 46^a. The bottom portion of the abutment 46 has formed integral therewith a pair of spaced aligned L-shaped lugs 46^b forming grooves 46^c. The top and bottom edges of the section 36 are indicated at 47, 48 respectively. The top edge 47 in proximity to each end thereof is formed with an arcuate offset portion 49 provided with an opening 50. The inner face of the upper part 38 of section 36 below top edge 47 is formed with a lengthwise disposed rib 51 spaced from the top of the rib 43. The front and rear edges of the section 36 are indicated at 52, 53 respectively. The inner face of section 36 is formed with a pair of vertical ribs 54, 55 flush respectively with the edges 52, 53. The rib 54 is of slightly less length than the rib 55. The inner face of section 36 is formed with a pair of vertical inner ribs 56, 57 disposed inwardly of and coacting respectively with the ribs 54, 55 to form the grooves 58, 59. The rib 51 merges into the upper ends of the ribs 56, 57 and into the rib 55 below the upper end of the latter. The ribs 56, 57 each is formed with a pair of spaced parallel superposed grooves 60. Integral with each inner rib and the inner face of section 36 are two superposed spaced pairs of spaced parallel lugs 61 which extend from an inner rib towards a side of the rib 43. A groove 60 is arranged between a pair of lugs 61. The front and rear parts 40, 41, of section 36 each has formed integral with its inner face a T-shaped support 62 spaced inwardly of an inner rib. The purpose of the supports 62 will be hereinafter referred to. The inner face of the bottom part 39 is formed with a rib 63 which is flush with the edge 27 and merges at its ends into the lower ends of the ribs 56, 57. The inner face of

section 36 is formed with spaced integral reinforcing ribs 64 interposed between the rib 43 and the ribs 51, 56, 57 and 63.

The section 37 of a side member comprises a sheet metal panel-like body 65 of rectangular contour positioned against an abutment 44 and surrounded by a shoulder 45, and when so positioned it will be removably positioned in the grooves formed by the lugs 46, 46^b and will be detachably connected to said sections 36 by said lugs. These latter are disposed at the corners of the abutment.

The ribs 51 of the side members 13, 14 coact to provide a support for a purpose to be referred to. Each side member at its upper end is formed with an outwardly directed flat flange 68 provided with spaced integral depending reinforcing webs 69. Each side member at its sides is formed with outwardly directed flanges 70 and its bottom with an outwardly directed flat flange 71. The flanges 68, 71 are of greater width than the flanges 70. The flanges 68, 70, 71 merge into each other.

The rear member 15 (Figures 5 and 6A) is formed of an outer section 72 of frame-like contour and an inner section 73 of panel-like form. The section 72 is formed of an upper part 74, a lower part 75 and a pair of side parts 76, 77. The inner and outer edges of the section 72 are indicated at 78, 79 respectively. The inner face of section 72 is formed with an inner endless rib 80 spaced from the edge 78 and which provides the said inner face with an abutment 81 and a shoulder 82 surrounding the abutment. The latter has its upper portion integral with a pair of aligned spaced offset inverted L-shaped lugs 83 forming grooves 83^a. The bottom portion of the abutment 81 has formed integral therewith a pair of aligned offset L-shaped lugs 83^b forming grooves 83^c. The inner face of section 72 is formed with an outer endless rib 84 having a pair of opposed portions flush with parts of the outer edge 78 and another pair of portions spaced from the remaining parts of said outer edge. Each of said portions spaced from said edge 78 is formed with a pair of spaced inset parts. The side parts of the section 72 each is formed with a pair of superposed openings 85. The lower parts 75 of section 72 between the ribs 80, 84 is formed with a rectangular opening 86 controlled by a pivoted damper 87 (Figure 11) attached to the rear face of said lower part 75. The rib 80 corresponds in form to the form of the rib 43 of a side member. The rib 84 corresponds in form to the outer rib on the inner face of the front member 12. The openings 85 are arranged relative to the inset parts of the rib 84 in the same manner as the openings 25 of member 12 are disposed relative to the inset parts 29 of the outer rib of member 12. The inner face of section 72 is formed with integral reinforcing ribs 88 arranged between the ribs 80, 84.

The section 73 of rear member 15 corresponds in form to the form of section 37 of a side member. The section 73 of rear member 15 is arranged relative to and detachably connected to the said section 72 in the same manner as section 37 of a side member is arranged relative to and detachably connected to the section 36 of the side member. The lugs 83, 83^b are arranged at the corners of abutment 81. The upper and lower ends of the section 72 are formed with a pair of outwardly directed flat flanges 89, 90. The flange 89 constitutes a support for a purpose to

be referred to and it is formed with spaced protuberances 91.

With reference to Figure 6^a, it discloses the relative positions of the front, rear and side members when they are assembled to form the body 16, and in this connection the member 12 extends in the front grooves 58 and the member 15 extends into the rear grooves 59 of the side members 13, 14. Holdfast means 92 coact with the openings 25 of member 12, the openings 85 of the member 15 and the pairs of lugs 61 on the side members 13, 14 for detachably connecting said members 12, 13, 14, 15 together to form the open top and bottom body 16. The inturned portion 28 of front member 12 and the inturned portion of the rib 84 of the member 15 form clearances for the lugs 61. The holdfast devices or means 92 are seated in the grooves 60.

The body 16 is divided into a fire box or chamber and an ash pit and for such purpose a removable grate 93 is employed and which is mounted on the T-shaped supports 62 aforesaid provided on each side member. The fire box or chamber is indicated at 94 and the ash pit at 95, Figure 3.

The pair of openings 50 of one side member align with the pair of openings 50 in the other side member. Mounted in each pair of aligned openings and suitably connected to the side members is a pivot bar or rod 96. The stove structure includes a grille formed of a pair of oppositely disposed like sections 97, each has its outer end of reduced width and rounded, as at 97^a. The said reduced end is hollow and loosely encompasses a pivot rod 96 whereby the section is hinged to the rod. The sections of the grille are to normally seat on and be supported by the ribs 51 on the inner faces of the side members 13 and 14. The grille sections may be shifted to a vertical position to enable convenient access to the chamber 94 from the top of the latter. The stove structure includes a pair of oppositely disposed cover sections 98, 99 for the grille when the latter is not used. The cover sections are of like form and each has its outer end formed with a pair of spaced aligned apertured ears 100 loosely encompassing a pivot rod 96 whereby the cover section is hinged to said rod. The reduced outer end 97^a of a grille section is arranged between a pair of ears of a cover section, whereby the latter may be shifted independently of a grille section. When the cover sections are closed they are mounted on the grille sections. Each cover section has its outer face formed with a pair of spaced aligned abutment members 101 formed of a body part 102 having its outer end provided with an offset extension 103. The cover sections also constitute supports for various objects when such sections are extended laterally with respect to the front and rear of body 16, and when so extended they will appear as shown by Figure 2, that is sections 98, 99 will be supported on flanges 34, 89 of members 12, 15 and with the extension 103 of the abutment members 101 arranged under and coacting with the flanges 89, 90 for bracing the cover sections. When the cover sections are extended to constitute supports, they are arranged below the upper end of body 16.

With reference to Figures 7, 8, 9 and 10, the modified form of outdoor stove structure, in accordance with this invention is generally indicated at 105, and it includes a chimney 106, a stove body 107 having sides, front, bottom and rear built in the lower portion of the chimney, and an oven 108 arranged within the chimney above and rearwardly of the body 107. Certain

of the elements of the oven have portions thereof built into the chimney.

The chimney 106 may be formed of courses of brick or stone, cement, concrete or other suitable masonry and it includes a pair of side walls 109, 110 of like form, a bridge or arch 111, a front wall 112, a rear wall 113 of greater height than said front wall, a bottom wall 114 and a base 115. The rear part 114^a of the bottom wall 114 is of greater height than its front part 114^b. Each side wall consists of an upper part 116, an intermediate part 117 and a lower part 118. The part 116 is of greater height than the part 117. The part 116 is of less height than the part 118. The part 117 is of less width and height than the part 118. The latter is of greater thickness than the parts 116, 117. The part 117 extends outwardly from the part 116. The part 118 extends outwardly from and is laterally offset with respect to part 117, as at 119.

The wall 112 merges into the front of the parts 116 and into the rear of the top of the parts 117. The bridge or arch 111 merges into the top of the parts 117 and into the lower portion of the front of the wall 112. The parts 117 merge into the rear portion of the top of the parts 118. The rear ends of the side walls merge into front face of the rear wall 113. The lower ends of the side and rear walls merge into the upper face of the bottom wall 114. The latter merges into the base 115. The base 115 is laterally offset with respect to the sides and front of the bottom wall 114.

The manner of setting up the walls of the chimney provides the latter with an L-shaped chamber 120 having a horizontally disposed lower portion with its rear part of less height than its forward part and a vertically disposed upper portion extended from the rear part of the horizontal portion. The latter is open at its top and front and closed at the rear. The vertical portion is open at its front, partly closed at its top and closed at its rear. Certain of the walls of the chimney are so correlated to form a flue 121 opening at its lower end into the open top part of the said vertical portion of chamber 120. The level of the part 114^a of the bottom 114 is to be slightly above the grate within the stove body. There is arranged in the chimney structure a smoke ledge 121^a in the form of an angle iron which projects forwardly from and is secured to wall 113 and it is also secured to the top of the part 114^a of bottom 114.

The stove body 107 is of the same construction as the stove body 16, with this exception, that the inner sections of the side and rear members are not employed. The side members of the body 107 are indicated at 122, 123, the front member of body 107 is designated at 124 and the rear or back member of body 107 at 125. The members 122, 123 correspond in construction to the outer sections of the side members 13, 14. The front member 124 corresponds in construction to the front member 12. The member 125 corresponds in construction to the front member 12. The member 125 corresponds in construction to the outer section of the back member 15 with the exception that it is not provided with opening 86 and damper 87. The stove body 107 includes a pair of oppositely disposed cover sections 126, 127 for the grille 128, but in lieu of the cover section 127 functioning as a support when it is removed from over a grille section it provides the door for the oven 108.

The oven 108, in addition to its door provided by the cover section 127 includes a bottom 129, a

back wall 130, a top wall 131 and a pair of side walls 132. The bottom 129 is provided by a rearwardly extending horizontally disposed plate 133 mounted at its front end on the upper flange 89 of member 125. The plate 133 at its sides is formed with ribbed offset flanges 134 which are embedded in the upper portions of the inner faces (Figure 10) of the parts 116 of the side walls of the chimney. The plate 133 is of a length to extend to align with the inner face of wall 112 and is formed with apertures 135 in proximity to its rear edge. The back wall 130 of the oven is formed from a vertically disposed plate 136 having studs 137 on its bottom edge engaging in the apertures 135. The bottom edge of plate 135 bears upon the upper face of plate 133. The sides of plate 136 are embedded in the inner faces of the parts 116, 117, 118 of the sides of the chimney. The top portion of plate 135 is embedded in the lower end of the front wall 112. The top wall 131 of the oven is provided by the lower face of the bridge or arch 111 and the lower end of the wall 112. The side walls 132 of the oven are formed by the inner faces of the parts 117, 118 of the chimney. The rear face of the plate 136 is flush with the inner face of the wall 112. The oven 108 is arranged in the vertical portion of the chamber 120. The open front of the vertical portion of chamber 120 is the open front of the oven and which is to be closed by the cover section 127.

The stove body 107 is arranged between the forward portion of the side walls of the horizontally disposed portion of the chamber 120, and it is not only built in such side walls, but also into the said bottom part 114 of the chimney structure. The part 114 forms the bottom of chamber 120. When body 107 is built-in the parts 118 of the side walls of the chimney, the inner faces of such parts close the side members 122, 123 of the stove body 107. The high part 114a of the bottom 114 closes the member 125 up to about two inches above the grate. Access is had to the top of stove body 107 from that part of the open top of chamber 120 forwardly of the vertical portion of said chamber, and access is had to the front of stove body 107 from the open front of chamber 120. When the stove body 107 is built-in the bottom of the chimney, the front of said body is substantially flush with the front of the lower portions of the sides of the chimney. The top and front of the stove body are permanently exposed.

It will again be stated that the construction of the stove body 107 is the same as the construction of the stove body 16 with this single exception that the stove body 107 does not include the inner sections of the side and back members of the stove body 16 and the damper.

Preferably the outer sections of the rear and side members of the stove body 16 will be of cast iron and their inner sections of sheet metal of the desired thickness. The rear and side members of the stove body 107 will be the outer sections of the rear and side members of the body 16. The front members of the stove bodies 16 and 107 will be cast iron.

What I claim is:

1. An outdoor stove structure including a front member, a pair of side members, a rear member, means for detachably connecting said members together to form an upstanding body open at its top and bottom, said side members being extended above the upper ends of said front and rear members and being apertured at their upper

ends in proximity to their front and rear ends, said front and rear members having outwardly directed flanges at their upper ends, a grate supported by said side members below said upper ends of the latter to form said body with a fire chamber and an ash pit, said front including selectable closable entrances for said chamber and ash pit, a grille formed of a pair of oppositely disposed selectable shiftable sections each having a continuous rounded hollow outer end of less width than and inset with respect to the sides of the remaining portion of the section, a cover for the grille formed of a pair of oppositely disposed selectable shiftable sections each having its outer end formed with a pair of spaced parallel outwardly extending apertured ears between which is arranged a rounded outer end of a grille section, a pair of spaced parallel pivot members having their terminal portions mounted in the openings of said side members, each pivot member being common to the rounded outer end of a grille section and the pair of apertured ears of a cover section and connected thereto, said side members being provided with means on their inner faces below their upper ends for supporting said grille sections stationary in horizontal alignment, said cover sections having abutment means on their outer faces adjacent their outer ends for correlation with the lower faces of the flanges on said front and rear members for bracing the cover sections when extended laterally from said front and rear members.

2. An outdoor stove structure including a front member, a pair of side members, a rear member, means for detachably connecting said members together to form an upstanding body open at its top and bottom, said side members being extended above the upper ends of said front and rear members and being apertured at their upper ends in proximity to their front and rear ends, said front and rear members having outwardly directed flanges at their upper ends, a grate supported by said side members below said upper ends of the latter to form said body with a fire chamber and an ash pit, said front including selectable closable entrances for said chamber and ash pit, a grille formed of a pair of oppositely disposed selectable shiftable sections each having a continuous rounded hollow outer end of less width than and inset with respect to the sides of the remaining portion of the section, a cover for the grille formed of a pair of oppositely disposed selectable shiftable sections each having its outer end formed with a pair of spaced parallel outwardly extending apertured ears between which is arranged a rounded outer end of a grille section, a pair of spaced parallel pivot members having their terminal portions mounted in the openings of said side members, each pivot member being common to the rounded outer end of a grille section and the pair of apertured ears of a cover section and connected thereto, said side members being provided with means on their inner faces below their upper ends for supporting said grille sections stationary in horizontal alignment, said side members being formed on their inner faces with spaced means to provide for the interengaging therewith of the front and rear members when the said several members are detachably connected together to form said body, each of said side members at the front and rear being provided with a depending leg, and said cover sections having abutment means on their outer faces adjacent their outer

ends for correlation with the lower faces of the flanges on said front and rear members for bracing the cover sections when extended laterally from said front and rear members.

3. An outdoor stove structure including a front member, a pair of side members, a rear member, means for detachably connecting said members together to form an upstanding body open at its top and bottom, said side members being extended above the upper ends of said front and rear members and apertured at their upper ends in proximity to their front and rear ends, a grate supported by said side members below said upper ends of the latter to form said body with a fire chamber and an ash pit, said front including selectable closable entrances for said chamber and ash pit, a grille formed of a pair of oppositely disposed selectable shiftable sections each having a continuous rounded hollow outer end of less width than and inset with respect to the sides of the remaining portion of the section, a cover for the grille formed of a pair of oppositely disposed selectable shiftable sections each having its outer end formed with a pair of spaced parallel outwardly extending apertured ears between which is arranged a rounded outer end of a grille section, a pair of spaced parallel pivot members having their terminal portions mounted in the openings of said side members, each pivot member being common to the rounded outer end of a grille section and the pair of apertured ears of a cover section and connected thereto, said side members being provided with means on their inner faces below their upper ends for supporting said grille sections stationary in horizontal alignment, said front and rear members being formed at their tops with outwardly directed right angular extending flanges constituting supports for the cover sections when the latter are extended, and said cover sections being formed with means for correlation with said flanges for bracing such sections when extended outwardly and for limiting the extent of the shifting of such sections in an outward direction.

4. In an outdoor stove structure, a chimney structure having an open front portion and with

the upper part of said portion inset with respect to the lower part of such portion whereby said lower part will extend forwardly from said upper part, a stove body built in the forwardly extended part of said open front and including a fire chamber, an ash pit, a top and a forwardly directed normally horizontally disposed shiftable member seated on and hinged at its rear end to the rear end of said top, means supported by and 10 extended rearwardly from the top of said stove body, embedded in and correlating with the chimney structure to form an open front oven rearwardly of and above said stove body, said member capable of being shifted rearwardly and 15 upwardly to abut the front of the chimney structure to provide a closure for the open front of said oven, and said stove body having its front and its top permanently exposed and its front provided with means for selectable access to said 20 chamber and ash pit.

5. In an outdoor stove structure including a hollow front portion open at its forward end and throughout its top, a forwardly directed hollow intermediate portion extending above and merging at its lower part into the rear of said front portion and a flue forming portion, said intermediate part opening at its rear end into said flue, opening at the front of its lower part into the rear of said front portion and opening at the 25 front of its upper part into the atmosphere above and at the rear end of said front portion, a chimney structure, a stove of the grille type built-in said front portion and communicating with the lower part of said intermediate portion, said stove having its top and front permanently exposed, and means supported from the rear of the stove, embedded in the upper part of said intermediate portion and correlating with the latter to form an open front oven arranged above and 30 extended rearwardly from the stove, and said stove including a hinged part at its top engageable with the front of the upper part of said intermediate portion for closing the open front of the oven.

STANLEY C. HESTER.
